HARRY H. LABADIE AND BURTON B. BEERS, OF CHICAGO, ILLINOIS, ASSIGNEES TO
KNICKERBOCKER CASE COMPANY, OF CHICAGO, ILLINOIS, A CORPORATION OF
ILLINOIS

COMBINED SAMPLE CASE AND DISPLAY STAND

Application filed April 9, 1930. Serial No. 442,837.

This invention relates to certain new and useful improvements in a combined sample case and display stand, and more particularly to a sample case embodying a display board adapted to display ladies' stockings or other long articles in substantially fully extended positions, and at the same time carry an auxiliary supply of similar articles so that the articles on the display board need not be removed.

Briefly described, the invention includes a carrying case consisting of a main tray section, and a removable cover. The display board consists of a plurality of similar display members which, in collapsed position, are adapted to be stacked in superposed parallel relation upon the tray and enclosed within the cover member. The lowermost display member is hinged to the tray member, which acts as a support when placed in a horizontal position. The several display members are joined at their ends by a plurality of links which form a lazy-tong construction whereby the members may be extended into an upwardly inclined position slightly overlapping one another at their adjacent ends. Each display member includes a display board mounted in an inclined position between the end members of the section, so that when the several display sections are moved to extended position, the several display boards will be substantially in alignment in approximately a single plane so as to form a single continuous display member or board. Spring clamps are provided on the several units of the display board whereby the stockings or other articles can be held in extended position across the several members of the board, but may be folded between the several board units when the display board is collapsed. The lazy tong constructions embody means for locking the display board in upright extended position.

The principal object of this invention is to provide a combined sample case and display stand, such as briefly described hereinabove, and disclosed more in detail in the specifications which follow.

Another object is to provide an improved

form of foldable display board for use in a sample case.

Another object is to provide an improved form of combined sample case and display stand adapted to simultaneously display a plurality of articles in extended position and carry an accessible supply of similar articles.

Another object is to provide a device that may be used alternatively as a carrying case or display stand, or combine both of these features.

Other objects and advantages of this invention will be more apparent from the following detailed description of certain approved forms of apparatus embodying the principles of this invention.

In the accompanying drawings:

Fig. 1 is a perspective view of the sample case in closed position.

Fig. 2 is a similar view of the sample case with the cover removed.

Fig. 3 is a view similar to Fig. 2, but showing the display board in extended position.

Fig. 4 is a plan view of the tray member or supporting base, on a larger scale, with the display board broken away.

Fig. 5 is a detail vertical section, taken substantially on the line 5—5 of Fig. 4.

Fig. 6 is a front elevation of the supporting tray and display board in upright position.

Fig. 7 is a transverse vertical section taken substantially on the line 7—7 of Fig. 6.

Figs. 8 and 9 are views similar to Figs. 6 and 7 respectively, but showing a modified form of display board.

The carrying case comprises a pair of mating sections 1 and 2 of similar exterior construction, the section 1 serving as a sample-holding tray and as a base or support for the display board, when placed in a horizontal position on a supporting surface, and the other section 2 serving as a removable cover member. A carrying handle 3 is secured to one of the members, in the example here shown to the cover member 2, and clamps or locking members 4, of any suitable and well known type, are mounted on the ends of the sections to detachably lock the sections together in closed position, as

shown in Fig. 1. When the sample case is to be opened and the articles displayed, the case is laid on its side, as shown in Fig. 1, the clasps 4 are unlocked, and the cover 2 is removed, the remainder of the device then appearing as shown in Fig. 2.

The tray member 1 may be provided with a plurality of interior partitions 5, thus dividing the tray into a plurality of compartments 6 in which different types of stockings or other articles may be carried. A metal supporting plate 7 is secured to the inner face of each end wall 8 of the tray. Each plate 7 is formed at its upper edge with an inwardly extending flange 9, from which projects an upwardly extending flange 10, to which latter flange the elements of the display board, hereinafter described, are pivotally attached.

The display board comprises a plurality of similar display sections or members A, B and C. While three of these sections are shown in the present example, it will be apparent as the description proceeds, that any reasonable number of these sections might be used, in accordance with the dimensions of the display board required and the size of the carrying case. Each of these sections comprises a pair of similar metal end frames 11 and 12, arranged parallel with one another and connected by a flat display board 13. These end-frames are preferably in the form of channel sections, opening inwardly or toward one another, whereby the requisite strength may be obtained from stampings of rather thin sheet metal. The display board 13 is, for reason that will be hereinafter apparent, mounted in a diagonal position between the end frames 11 and 12 (best shown in Fig. 7), that is the display board extends from the upper rear corners to the lower front corners of the end frames 11 and 12, when the sections are arranged in collapsed position, as shown in Fig. 2. This arrangement of the several display boards 13 permits the several boards to extend substantially in continuation with one another, or practically in a single plane, when the several display sections are extended to the overlapping position shown in Fig. 7.

A longitudinally extending frame bar 14 is riveted or otherwise secured to the outer side of each end frame 11 and 12 of each of the sections B and C, or of all of the sections except the lowermost section A, in case a greater number than three are used. A somewhat similar frame bar 15 is secured to each end of the lowermost section A, except that this bar 15 is provided with a downwardly extending end portion 16 which is pivoted at 17 to the flange 10 of the supporting wall 7 mounted in the tray 1. In this manner the lowermost tray A is pivoted directly to the tray 1 and may be swung from the horizontal position shown in Fig. 2 to the upwardly

inclined position shown in Figs. 3, 6 and 7. A link or lever 18 is centrally pivoted at 19 to the central portion of bar 14 on section B, and is pivoted at its upper end 20 to the front end of bar 14 on section C, and is pivoted at its other end 21 to the rear end of bar 15 on section A. In case a greater number of sections than 3 is used, it is to be understood that links similar to 18 will connect all of the intermediate sections of the series. A shorter link 22, which corresponds to the lower half of link 18, is connected at its upper end 23 to the center of bar 14 on upper section C, and at its lower end 24 to the rear end of bar 14 on section B. A link 25 is intermediately pivoted at 26 at the center of bar 15 on lower section A, and is pivoted at its upper end 27 to the front end of bar 14 on section B. The lower end of link 25 is pivoted at 28 to a link 29 which is pivoted at its lower end 30 to the flange 10 of supporting plate 7. It is to be understood that the system of lazy-tong links just described is duplicated at each end of the several sections A, B and C.

With the parts in collapsed position, as shown in Fig. 2, it is merely necessary to lift up on the upper display section C, and the several sections will automatically extend themselves to the positions shown in Figs. 3, 6 and 7, in which the front or lower edge of one section rests against the upper or rear edge of the section directly below. As the parts approach this extended position, the pivotal connection 28 between links 25 and 29 will cross the line connecting centers 26 and 30 and move to the position shown in Figs. 3 and 7, in which position the links 29 act as supports to lock the display board in its upwardly inclined position.

In order to lower the display board, the upper section C is grasped and the assembly is first swung forward so as to swing the pivotal connection 28 to the other side of the line connecting pivots 26 and 30, whereafter the parts will automatically collapse to the position shown in Fig. 2.

One or more spring clamps 31, of any suitable form, are mounted on each of the display sections A, B and C. In the well known form here shown, the ends 32 of the looped rod 31 are pivoted in the end frames 11 and 12, and torsion springs 33 tend to hold the transversely extending portion 34 of the rod in yieldable engagement with the front face 120 of the display board 13.

The stockings or similar articles are placed in position against the aligned faces on the several display boards 13 and clamped in place by the spring pressed rods 34. The upper ends of the stockings may be folded over the upper edge of display section C, or may be folded down over the uppermost rod 34, as shown in Fig. 3. In the latter case, any suitable sign or emblem or other

display means may be mounted on the upper portion of the uppermost display board 13, as at 35 in Fig. 3. Such a sign or other display could be stamped directly on the upper portion of the display board 13, or could be attached thereto, in any suitable manner.

While this display case has been designed more particularly for displaying ladies' hosiery, it will be understood that it is also adapted for displaying neck-ties, suspenders, gloves, or socks, or any other articles of this kind. The improved display case is particularly advantageous for displaying articles of considerable length which may be extended over the aligned display boards. It will be understood that when the apparatus is collapsed, as shown in Fig. 2, the articles secured in display position will fold themselves between the several display members. It will be understood that the improved display stand embodied in this carrying case could be used for window display or similar purposes. In such event it could be mounted on a simpler form of base or standard instead of the tray 1, here disclosed, although the carrying case here shown might be used for this purpose.

When used as a salesman's sample case, a supply of the hosiery or similar articles displayed on the display board can be carried in the sections 6 of the tray 1. When the device is moved to the display position shown in Figs. 3, 6 and 7, it is unnecessary to remove the samples which are attached to the display board for show purposes, but similar articles loosely carried in the tray 1 may be removed for further inspection.

In Figs. 8 and 9, a somewhat modified form of display board is disclosed. The end frames 11 and 12 and the connecting lazy tongs may be identical with those already described. Instead of the continuous flat display boards 13, a plurality of parallel horizontally extending rods 36 connect the end frames 11 and 12, the spring clamp 31 which may be of the same form as already described, being mounted so as to cooperate with certain of these cross rods 36, as shown in Figs. 8 and 9, whereby the hosiery or other articles are clamped between these rods 34 and 36. This form of display board has certain advantages when articles such as silk hosiery is displayed since the display board or rack is transparent so that the light may pass through the articles being displayed. It will be noted that the cross-rods 36 are arranged in diagonal alignment between the side frames 11 and 12 so that they will approach as closely as possible to being positioned in a single plane, as in the case of the display boards 13 shown in the first form of the invention.

We claim:

1. A foldable display stand comprising a supporting base, and a foldable substantial-

ly flat display board comprising a plurality of substantially flat display members, and means hingedly connecting the members to one another and to the base, whereby the members may be moved from collapsed position in superposed horizontal relation upon the base, to an upwardly inclined position with the members in substantial alignment to form the single substantially flat display board.

2. A foldable display stand comprising a supporting base, and a foldable substantially flat display board comprising a plurality of substantially flat display members, means hingedly connecting the members to one another and to the base, whereby the members may be moved from collapsed position in superposed horizontal relation upon the base, to an upwardly inclined position with the members in substantial alignment to form the single substantially flat display board, and a plurality of clamping devices attached to the several members and adapted to engage intermediate portions of articles mounted on the board and extending continuously across the several members.

3. A foldable display stand comprising a supporting base, and a foldable substantially flat display board comprising a plurality of substantially flat display members, means hingedly connecting the members to one another and to the base, whereby the members may be moved from collapsed position in superposed horizontal relation upon the base, to an upwardly inclined position with the members in substantial alignment to form the single substantially flat display board, and a spring clamp attached to each display member for grasping an intermediate portion of a foldable article positioned on said display board so as to extend across said several members, whereby the article may be folded between the members when the stand is collapsed.

4. A foldable display stand comprising a base, a plurality of substantially flat display members, each comprising a pair of parallel end frames and a flat display board supported between the frames and inclined from the upper rear corner of the frames to the lower front corner, and links hingedly connecting the side frames to one another and to the base whereby the display members may be moved from collapsed position with the several sets of end frames in superposed parallel relation to an upwardly inclined position with the display boards positioned in substantial alignment in approximately a single plane so as to form one continuous display board.

5. A foldable display stand comprising a base, a plurality of substantially flat display members, each comprising a pair of parallel end frames and a flat display board supported between the frames and inclined from

the upper rear corner of the frames to the lower front corner, links hingedly connecting the side frames to one another and to the base whereby the display members may be moved from collapsed position with the several sets of end frames in superposed parallel relation to an upwardly inclined position with the display boards positioned in substantial alignment in approximately a single plane so as to form one continuous display board, and a plurality of spring clamps attached to the several boards.

6. A foldable display stand comprising a base, a plurality of substantially flat display members, each comprising a pair of parallel end frames and article supporting members extending between the frames and lying substantially in a plane inclined from the upper rear corner of the frames to the lower front corner thereof, and links hingedly connecting the side frames to one another and to the base whereby the display members may be moved from a collapsed position with the several sets of end frames in superposed parallel relation to an upwardly inclined position with the article supporting members positioned in substantially a single plane so as to form one continuous display panel.

7. A foldable display stand comprising a base, a plurality of substantially flat display members, each comprising a pair of parallel end frames and article supporting members extending between the frames and lying substantially in a plane inclined from the upper rear corner of the frames to the lower front corner thereof, and links hingedly connecting the side frames to one another and to the base whereby the display members may be moved from a collapsed position with the several sets of end frames in superposed parallel relation to an upwardly inclined position with the article supporting members positioned in substantially a single plane so as to form one continuous display panel, and a plurality of spring clamps associated with the several supporting members to hold articles in engagement therewith in any position of the members.

8. A combined sample case and display stand comprising a base tray, a removable cover therefor, and a foldable display board comprising a plurality of display members adapted to be stacked in superposed relation upon the tray and enclosed by the cover, the lowermost display member being hinged adjacent one longitudinal edge to the tray, a plurality of links connecting the several display members whereby they may be extended to an upwardly inclined position in substantial alignment with one another to form the single continuous display board, locking links cooperating with the first mentioned links to hold the display members in extended position, and means for holding articles against the board in display position.

9. A combined sample case and display stand comprising a base tray, a removable cover therefor, and a foldable display board comprising a plurality of display members adapted to be stacked in superposed relation upon the tray and enclosed by the cover, the lowermost display member being hinged adjacent one longitudinal edge to the tray, a plurality of links connecting the several display members whereby they may be extended to an upwardly inclined position in substantial alignment with one another to form the single continuous display board, locking links cooperating with the first mentioned links to hold the display members in extended position, and spring clamps carried by the several display members to hold articles in extended display position on the display board.

10. A combined sample case and display stand comprising a base tray, a removable cover therefor, and a foldable display board comprising a plurality of display members adapted to be stacked in superposed relation upon the tray and enclosed by the cover, the lowermost display member being hinged adjacent one longitudinal edge to the tray, a plurality of links forming lazy-tongs connections between the several display members, locking links connecting the free ends of the lowermost links of the series with the tray, each display member comprising a display board so positioned that the several boards will be brought into approximate alignment in substantially a single plane to form the single continuous display board when the members are extended to display position.

11. A combined sample case and display stand comprising a base tray, a removable cover therefor, and a foldable display board comprising a plurality of display members adapted to be stacked in superposed relation upon the tray and enclosed by the cover, the lowermost display member being hinged adjacent one longitudinal edge to the tray, a plurality of links forming lazy-tongs connections between the several display members, locking links connecting the free ends of the lowermost links of the series with the tray, each display member comprising a display board so positioned that the several boards will be brought into approximate alignment in substantially a single plane to form the single continuous display board when the members are extended to display position, and spring clamps carried by the display members and adapted to engage intermediate portions of articles displayed in extended position upon the several members of the display board.
